UNITED STATES PATENT OFFICE.

WILLARD JAY WOODCOCK, OF BROOKLYN, NEW YORK.

ADJUSTABLE DISTRIBUTER FOR INTERNAL-COMBUSTION ENGINES.

1,349,308.

Specification of Letters Patent. Patented Aug. 10, 1920.

Application filed November 13, 1917. Serial No. 201,815.

To all whom it may concern:

Be it known that I, WILLARD JAY Woodcock, a citizen of the United States, and resident of Brooklyn, in the county of Kings 5 and State of New York, have invented certain new and useful Improvements in Adjustable Distributers for Internal-Combustion Engines, of which the following is a specification.

10 My invention relates to an adjustable distributor for internal combustion engine using compressed air or any similar agent.

At the present time there is no distributing disk known to me which has ports so arranged that air under pressure is admitted to more than one cylinder at a time, and three cylinder engines especially are apt to stop in such a position that no port is open to admit air, or arranged so that the engine 15 can be started ahead or astern as desired.

The object of my invention is to provide means for admitting air into two or more cylinders of a multi-cylinder internal combustion engine at certain positions of the 20 crank circle which will make the rotation thereof positive, so the engine will start in either direction.

The method of obtaining these results is illustrated in the accompanying drawings. 25 Figure 1 shows a sectional elevation.

Fig. 2 shows the elevation.

Fig. 3 shows an end view.

Fig. 4 shows a plan of the position of the ports for the "ahead" motion when crank 30 No. 1 is on the top center.

Fig. 5 shows a plan of the position of the ports for the "astern" motion when crank No. 1 is on the top center.

Fig. 6 shows the face of the adjustable 35 disk in position for ahead motion when No. 1 crank is on the top center.

Fig. 7 shows the face of the rotating disk in position for ahead motion when No. 1 crank is on the top center.

40 Reference being made to the accompanying drawings, Fig. 2, Sheet 1, 33, represents the frame which is attached to the engine by bolts passing through the holes 36, 37, 38 and 39 and contains the bearings 34 and 35 and also the chamber 4 Fig. 1 which is bored to receive the rotating disk 5 and the adjustable disk 6. The head 7 is bolted to it. The rotating disk 5 is fast to the shaft 8 as is also the gear 9 which meshes 45 in the gear 10, Fig. 4, which is fast on the

crank shaft and therefore drives the rotating disk at the same speed as the crankshaft, the gears being the same diameter.

The rotating disk 5, Fig. 7, has in this case three ports, 11, 12, and 13, which connect with the three cylinders actuating No. 1, 2 and 3 cranks set at 120 degrees respectively. These cylinders are not shown and the ports referred to are respectively on the same radius as the ports 14, 15 and 16 in the adjustable disk 6, Fig. 6, whose face is kept in contact with the face of the rotating disk 5 shown in Fig. 1, by the spring 17 and also by the pressure of air when it is in service.

In the back face of the adjustable disk, or 50 the face in contact with the head 7, Fig. 1, are cut three channels, 18, 19 and 20, Fig. 4, which are the same radius as the ports 14, 15 and 16 and furnish free passage for the air to the outlet ports 21, 22 and 23 in the head, 55 in which are located the pipe connections 24, 25 and 26, Fig. 3, which are connected by pipes to the three cylinders not shown, the arrangement being so well known.

The bell crank 46, Fig. 2, is fast to the 60 adjustable disk shaft 27, which is also fast to the adjustable disk 6 shown in Fig. 1.

The slotted lever 28, Fig. 3, engages the bell crank 46, Fig. 2, and is fast on the rock shaft 29 as is also the starting and reverse 65 lever 30, which engages with quadrant 31, Fig. 3, which holds it in position.

In setting the device above described for operation. The crank pin No. 1, Fig. 4, is placed on the top center, and the port 11 70 Fig. 7, which admits air to No. 1 cylinder is set line 47 to line 48, with the port 14 in the adjustable disk 6, Fig. 6, when in this position, as shown in Figs. 4, 5 and 7 air is admitted to No. 1 cylinder during 130 75 degrees of the crank circle.

The cranks are set at 120 degrees, and after moving this distance in the direction indicated by the arrowhead the port 12 Fig. 7 is then line and line with the port 15 Fig. 6 80 and No. 2 crank will be on the top center, and during the following 10 degrees of the crank circle the air is on No. 1 and 2 cylinders, or in other words No. 1 crank pulls No. 2 crank 10 degrees past the top center before 85 air is cut off No. 1 cylinder due to the line 49 of the port 11 passing by the line 50 of port 14 in the adjustable disk 6.

The same action takes place on all the 90 crank pins as they pass the top center and 95

therefore the action of the device is positive, and the engine will start with the cranks in any position.

The reverse motion is accomplished by moving the lever 30 to the astern position 40, Fig. 3, which moves the ports 14, 15 and 16 in the adjustable disk 6, Fig. 6, to the opposite end of the port 11, Fig. 7, and shown in position as described in Fig. 5. The device 10 is now set as before explained with No. 1 crank pin on the top center which has not been moved during this maneuver.

After the setting has been correctly made the position of the crank pins is of no consequence; the engine does start at any point in either direction according to the position of the starting and reverse lever 30, but when this lever is set at 42, Fig. 3, no air passes out of the pipe connection 24, 25 and 26, although the supply air is admitted through the supply pipe 32, because the bridges 43, 44 and 45, Fig. 6, and also shown at 43, Fig. 1, cover the outlet holes 21, 22 and 23 in the head 7, Fig. 5, thus causing 25 the engine to stop when operated by air under pressure, or other similar moving agent.

The grooves 18, 19 and 20 in the adjustable disk 6, Fig. 6, are continuous from the ports 30 14, 15 and 16 to their respective ends, as shown on the drawing, and provide a free passage to that extent, passing under a section of the face of the adjustable disk that is in contact with the head 7, Fig. 1, forming 35 the bridges 43, 44 and 45, which close the ports 21, 22 and 23 in the head 7, Fig. 5, and also shown by 43, in Fig. 1, when the lever 30 in Fig. 3 is placed in position 42 on the quadrant 31.

40 Having thus described my invention, what I claim as new is,

1. In an internal combustion engine, a distributor disk or valve having a port or ports,

and in contact with an adjustable disk valve or member having a port or ports with a connecting groove or grooves to provide a free passage to the port or ports in a stationary member with which it is in contact, and which has outlet openings, the said disk valves or members being incased and provided with an inlet opening and means provided to keep the surfaces in contact. 45 50

2. In an internal combustion engine, a distributor disk or valve provided with ports, and which is in contact with an adjustable disk valve or member provided with ports and grooves, and which is also in contact with a stationary member having ports and provided with outlet connections, the ports being so arranged that two or more outlets 60 65 have open passageway at the same time from the source of supply, the said disk valves or members being incased and provided with an inlet opening and means provided to keep the surfaces in contact.

3. In an internal combustion engine, a distributor disk or valve provided with ports and which is in contact with an adjustable disk valve or member provided with ports and grooves, and which is also in contact 70 with a stationary member having ports and provided with outlet connections; a valve seat to obstruct the passage from the source of supply to the outlet connections by placing the adjustable disk in a defined position, the 75 said disk valves or members being incased and provided with an inlet opening, and means provided to keep the surfaces in contact.

Signed at Brunswick in the county of 80 Glynn and State of Georgia this 10th day of September A. D. 1917.

WILLARD JAY WOODCOCK.
